INVENTOR

UNITED STATES PATENT OFFICE.

GERRIT RYPKEMA, OF WICHERT, ILLINOIS, ASSIGNOR OF ONE-HALF TO PETER J. CLAUSSEN, OF CHICAGO, ILLINOIS.

LUMBER-LOADING JACK.

No. 873,096.

Specification of Letters Patent.

Patented Dec. 10, 1907.

Application filed February 28, 1907. Serial No. 359,758.

To all whom it may concern:

Be it known that I, GERRIT RYPKEMA, citizen of the United States, residing at Wicherter, in the county of Kankakee and State of Illinois, have invented certain new and useful Improvements in Lumber-Loading Jacks, of which the following is a specification.

This invention is a lumber loading jack, adapted to be fixed in or attached to the doorways of freight cars or buildings for the purpose of protecting the door from injury and for providing or supporting rollers in convenient position so that the lumber may be rolled in thereon through the doorway.

15. The invention comprises means whereby the jack may be placed at any height desired in the doorway and also whereby an outer roller may be supported at any angle so that the lumber may be conveniently loaded or 20 unloaded from above or below.

The invention is illustrated in the accompanying drawings, in which

Figure 1 is a plan view thereof. Fig. 2 is an end view. Fig. 3 is a section on the line 25 3—3 of Fig. 1.

Referring specifically to the drawings, the door jambs to which the jack is attached are indicated at A. At 1 are indicated heads which are jammed or clamped against the 30 door jamb to hold the jack in position. These heads are connected by a rod 12, made in sections, joined at the adjacent ends by a turnbuckle 14, by means of which the heads may be tightened or loosened with respect to 35 the jambs. At each side of each head is an arm 20 carrying an upright roller 4, which serves to prevent the boards or timbers from catching or scraping against the door jamb when they are passed through the door at an 40 angle.

The heads support an inner roller 3 therebetween. This roller is hollow and has at the 45 ends rods 10 which project through caps 9 on the ends of the roller and rest at their projecting ends in bearings formed in the heads. The rods are extensible to accommodate the roller to doorways of different widths, and are fixed at adjustment by means of set screws 11 which extend through the caps and 50 bear against the rods. So the rods may be extended or retracted to proper length to rest at the ends in the bearings referred to.

Mounted upon the ends of the spacing rods 12 are sleeves 15 provided at their outer ends 55 with ratchet teeth 21 which engage corre-

sponding teeth at the adjacent ends of bosses or projections 15^a on the sides of the heads 1, and these bosses have sockets in which the ends of the rods 12 are fitted and fixed. The position of the sleeves 15 upon the rods 12 60 may be varied, and they are fixed as set by means of collars 13 and set screws 16. By loosening the screws the collars may be slipped back and the sleeves slid along until their teeth are disengaged, thereby permitting the sleeves to be turned on the rods.

At 5 are indicated arms which are bent around the sleeves 15 and clamped thereto by bolts 22. The outer ends of these arms are slotted as at 7 and support extensible sections 6, which are also slotted and which are adjustable in or out on the arms by means of the slots and the connecting bolts 8.

The outer ends of the arms 6 support a roller 2, which is similar in construction to 75 the roller 3 heretofore referred to. That is, it has rods 10 extensible endwise therefrom, and caps 9, and screws 11 to fix the rods as set. The outer ends of the rods rest in bearings on the outer ends of the arm sections 6. 80

By means of the sleeve and ratchet devices between the heads 1 the arms 5 may be set or inclined at any angle desired, thus supporting the roller 2 on a level with, or above or below, the roller 3. Thus, in loading a car 85 from below, the roller 2 will be placed somewhat lower, so that a piece of timber may be rolled up over the rollers 2 and 3 into the car. And the same in unloading a car to a lower position. In loading or unloading from or 90 to a higher position the roller 2 will be raised to the proper angle.

When the device is to be applied to a doorway the turnbuckle is turned to press the heads against the door jambs and fix the jack 95 in place at the desired height or position. The arms 5 are then set at the desired angle. The rollers 2 and 3 are then adjusted by means of their pivot rods to the necessary length, and placed in the bearings, and the 100 device is then ready for the use intended.

I claim:

1. A lumber jack having, in combination, a pair of heads connected together and having laterally extending arms provided with 105 upright rollers, and a horizontal roller extending between the heads and supported at its ends in bearings thereon.

2. A lumber jack having, in combination, an extensible support arranged to engage 110

door jambs or the like at opposite ends, a pair of arms projecting from said support and adjustable to various angles in a vertical plane, and a roller carried between the outer 5 ends of the arms.

3. A lumber jack having, in combination, a pair of heads, a screw rod connecting the same, arms projecting from the rod and adjustable angularly with respect thereto, and

extensible rollers respectively carried between the heads and between the arms.

In testimony whereof I affix my signature, in presence of two witnesses.

GERRIT RYPKEMA.
